[57] CLAIM

The ornamental design for a carrying case, substantially as shown and described.

DESCRIPTION

FIG. 1 is a front perspective view of a carrying case showing my new design;

FIG. 2 is a rear perspective view thereof showing the side pocket slightly open;

FIG. 3 is a top plan view thereof, with the side pocket shown slightly open; and

FIG. 4 is a top perspective view thereof showing the interior of the carrying case which includes an additional pocket shown in a slightly open configuration.

FIG. 1

FIG. 4
